(57) **CLAIM**

We claim the ornamental design for a vacuum cleaner, as shown and described.

DESCRIPTION

FIG. 1 is a bottom, front, right side perspective view of a first embodiment of a vacuum cleaner, showing our new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of the encircled portion 8 of FIG. 1;

FIG. 9 is a bottom, front, right side perspective view of a second embodiment of the vacuum cleaner;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is an enlarged view of the encircled portion 16 of FIG. 9.

The broken lines in the drawings show portions of the vacuum cleaner which form no part of the claimed design.

1 Claim, 16 Drawing Sheets
